UNITED STATES PATENT OFFICE.

GEORGE H. HAWES, OF RACINE, WISCONSIN.

VEHICLE-SPRING HEAD.

SPECIFICATION forming part of Letters Patent No. 577,428, dated February 23, 1897.

Application filed June 19, 1896. Serial No. 596,153. (No model.)

To all whom it may concern:

Be it known that I, GEORGE H. HAWES, a citizen of the United States, residing at Racine, in the county of Racine and State of Wisconsin, have invented certain new and useful Improvements in Vehicle-Spring Heads; and I do hereby declare the following to be a full, clear, and exact description of the invention, such as will enable others skilled in the art to which it appertains to make and use the same.

This invention relates to vehicle-spring heads.

My object is to provide a more simple, easily-assembled, and durable head for vehicle-springs of the leaf type, and this is accomplished by the employment of certain novel features and combinations appearing more fully hereinafter.

20 In the accompanying drawings, Figure 1 is a side elevation with one end of the coupling-box removed; Fig. 2, an end elevation looking in toward the cam coupling member and the clamping-nut, and Fig. 3 an end elevation looking toward the coupling-box and showing part of the same broken away to disclose the ends of the springs and the rear of the coupling member.

A and B designate the duplicate leaf-springs, and C the coupling box or head. The ends of the springs are provided with inwardly-curved ends, which comprise inner and outer cam-jaws 1 and 2, which narrow down very thin at their ends. The coupling-box is of substantially cylindrical outline, but its front half is cut away, so as to properly receive the ends of the springs, though the ends 3 and 4 of the coupling-box are circular. The rear inner wall of the coupling-box is 40 provided with curved depressions 5 and 6, in which the curved ends of the springs rest.

D designates the coupling member. It is provided with separated parallel rear curved cams 7 and 8, over which the jaws of the springs hook. The bottom of the open space between cams 7 and 8 is provided with grooves 9 and 10, which are separated by a ridge 11, and these grooves receive the thin ends of the jaws on the springs when the latter are spread far enough. The front of the coupling member is provided with a square nut-opening 12.

E designates a bolt which passes from the rear of the coupling-box through said box,

between the jaws of the respective springs, and through the coupling member.

55

F is a square nut through which the end of the bolt passes and which is received in the nut-opening 12, which prevents it from turning. After the parts have been assembled a blow on the bolt will rivet its end 60 down on the nut, and thus the parts will be held secure.

The cam-jaws are free to rock on each other and on the cams of the coupling member, as well as in the depressions in the coupling-box. The springs can thus suitably expand or contract, but their expansion is limited by the top and bottom walls of the coupling-box, as well as the abutment of the ends of the cam-jaws on the base between the cams of 70 the coupling member.

Having thus described the invention, what is claimed as new is—

1. In a carriage-spring head, the combination with a coupling-box, of springs having hooked cam ends, a coupling member having cams which fit in the hooked cam ends, and means for holding the coupling member in the box.

2. In a carriage-spring head, the combination with a coupling-box, of springs having hooked cam ends, a coupling member having cams which fit into the hooked cam ends, and a bolt passing through the coupling-box and coupling member, substantially as described.

85

3. In a carriage-spring head, the combination with a coupling-box having side walls and provided with inner curved depressions, of springs having cam ends located between the said walls and received in said curved 90 depressions, and means for preventing displacement from the coupling-box of the cam ends of the springs.

4. In a carriage-spring head, the combination with a coupling-box provided with interior curved depressions, of springs having hooked ends forming inner and outer cam-surfaces, the outer cam-surfaces being received in the curved depressions of the coupling-box, a coupling member having cams which fit in the inner cam-surfaces of the springs, and means for holding said coupling member in position.

95

5. In a carriage-spring head, the combination with a coupling-box provided with interior curved depressions, of springs having

100

105

hooked ends provided with inner and outer cam-surfaces, the outer cam-surfaces fitting in the curved depressions, a coupling member having cams which fit in the inner cam-
5 surfaces of the springs, and a bolt passing through the coupling-box and coupling member, whereby the latter is held within the former.

In testimony whereof I have signed this specification in the presence of two subscr-
ing witnesses.

GEORGE H. HAWES.
